(57) **CLAIM**

The ornamental design for a trash can lid with size indicia as shown and described.

DESCRIPTION

FIG. 1 is a top right-side perspective view of a first embodiment of a trash can lid with size indicia;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top plan view thereof;

FIG. 7 is a bottom plan view thereof;

FIG. 8 is a top left-side perspective view of a second embodiment of a trash can lid with size indicia;

FIG. 9 is a front elevational view thereof;

FIG. 10 is a rear elevational view thereof;

FIG. 11 is a right-side elevational view thereof;

FIG. 12 is a left-side elevational view thereof;

FIG. 13 is a top plan view thereof; and,

FIG. 14 is a bottom plan view thereof.

The dot-dash broken lines define the bounds of the trash can lid with size indicia. The dash-dash broken lines shown illustrate portions of the trash can lid with size indicia. The broken lines form no part of the claimed design.
